GRID FOR REFRIGERATOR FREEZING TRAYS

William Harrison Fuller, Jr., Dallas, Tex.

Application August 30, 1930, Serial No. 479,031

3 Claims. (Cl. 62—108.5)

This invention relates generally to removable ice cube grids used in conventional type of freezing trays and used in gas, chemical, or mechanical refrigerators, and particularly to a grid of improved character in construction which permits easier, quicker, and more satisfactory means of removing the ice cubes from the tray than is possible with ordinary types of grids.

It is an object of this invention to provide a removable grid of the class described, which by its nature and construction and the material from which it is composed, provides for easier removal of the ice cubes and more economical use thereof.

15 It is another object of this invention to provide an improved removable grid of the class described which may be used in the stead of the conventional type of grids in the conventional type of freezing trays, without alteration, and which will enable the use of the trays and make possible the removal therefrom of the ice cubes in the said improved manner.

It is also an object of this invention to provide an improved grid of the type described which permits removing the ice cubes either individually or as a whole in a group, as desired, and to enable said removal in a convenient, easy and satisfactory manner.

It is also an object of this invention to provide an improved removable grid of the type described, which is composed of a combination of flexible and semi-rigid material, the semi-rigid material forming a core upon which is formed the flexible material, and which does not noticeably retard the freezing of the water into ice cubes, but which because of the nature of the material permits more ready and satisfactory removal of the ice cubes from the tray.

These and other objects, the nature of the invention, its composition and arrangement and combination of parts will be readily understood from a reading of the following descriptions of the drawing, in which:

Figure 1 is a side elevation of a conventional ice cube freezing tray taken from one end thereof and showing the tray partly broken away to illustrate the disposition of my improved grid therein.

Figure 2 is a bottom view of my improved grid. 50 Figure 3 is a vertical transverse section through one of the elements in my improved grid illustrating the composition thereof and disclosing its formation with a core.

It is to be understood that I do not limit the 55 application of this invention to the particular

modification set forth herein to illustrate the same and any change or changes may be made in material and structure consistent with the spirit and scope of the invention.

Referring in detail to the drawing, a conventional ice freezing tray as indicated by the numeral 5 and my improved grid is indicated generally by the numeral 6. It will be obvious from the drawing that I provide the walls of my improved grid wedge-shaped tapering from the top 60 7 to the bottom 8 and formed of flexible rubber 65 as indicated at 9 and provided with a semi-rigid core 10. The upper edges of the walls as indicated at 11 and 12 are formed to enable the insertion of the grid into a freezing tray of conventional type so that it will fit therein snugly, without binding and permit easy removal.

It will be observed in Figure 3 that the flexible rubber or other suitable material is tapered from the top 7 to the bottom 8 of the walls of the grid, 75 and the core 10 is not tapered. It is thought to be obvious that the bottoms 8 of the walls of the grid are to be disposed in contact with the bottom 13 of the tray 5 and that the tops 7 of the said walls rise to a suitable height within the tray.

It is well known that the usual metal type of freezing tray has a removable metal grid which permits rapid freezing of the water into cubes because of the high conductivity of the metal. The removal of the ice cubes from such a tray involves a considerable waste and effort, as it is necessary first to run hot water over the bottom of the tray in order to loosen the cubes, which come out in one piece, and it is then necessary to again run hot water over the grid and the cubes to permit the removal from the grid, the entire operation consuming some time and resulting in the well known mishandling and consequent waste of the cubes. There is another type of tray employing a grid formed of material such as rubber, in which the grid and the tray are made as a unit or fastened together, which makes the removal of the cubes more easy than in the case of the metal grid and tray, but this type of grid and tray very considerably retard 90 the freezing of the water into ice cubes due to the low conductivity of the material. The metal type has the advantage of quick freezing, and the flexible material type has the advantage of simple and easy removal of the ice cubes. It will be evident by studying the invention disclosed herein that the advantages of both types of grids and trays are combined to produce a result partaking 100 of superior freezing quality and easy removal of the ice cubes. Since my device is adapted to be 105

110

used in a conventional metal tray, the large freezing surface of the tray coming in contact as it does with each compartment defined by the grid, will provide for complete distribution or conduction. The fact of the inclusion of my improved non-metallic grid, does not materially retard the freezing. It is obvious that when the water is frozen into ice cubes, a small amount of warm water applied to the bottom of the tray will quickly loosen the contents thereof in one piece. Then, due to the improved formation of my improved grid, it is necessary only to press the ice cubes with the fingers out of their compartments either singly or in the number desired. The operation is accomplished expeditiously, easily and without mishandling of the cubes, and it is accomplished by the semi-rigid nature of the structure used in the grid. This structure which permits the formation of the ice cubes having a large end and a small end which permits the ice cubes to be moved to better advantage toward the direction of the larger end, which movement is permitted and accelerated by the provision of the reinforced flexible material, the reinforcement being of semi-rigid material which facilitates the conduct of the slight pressure necessary to move the cubes from their position in the compartments of the grid. It is thought obvious that the use of my improved freezing tray grid permits rapid freezing of ice cubes and rapid and expeditious and convenient removal of the ice cubes when frozen, and permits the operation to be accomplished without mishandling and waste of the ice cubes.

It is therefore thought that it is understood I have provided an improved device of the character described, whose general nature may be varied in point of material and structure, but which announces a new and improved principle, which when applied according to the teachings of my invention, results in a superior device of the character described which constitutes a distinct and valuable contribution to the art to which it relates.

What is claimed is:—

1. A removable grid for a rigid metallic ice

cube freezing tray having flared wall, said removable grid comprising intersecting walls having angular ends engaging the walls of the tray, and a downwardly tapered cross section presenting a smaller edge for resting on the bottom of the tray, said walls comprising bodies of flexible compressible material, and plates of semi-rigid material therein forming cores of relatively large cross section, whereby sufficient force may be applied to the cubes when the grid is removed from the tray to dislodge them without unduly and injuriously deforming the walls.

2. A removable grid for a rigid ice cube freezing tray having slanted walls, said grid comprising a frame of intersecting semi-flexible plates, a thick covering on the plates of compressible material and forming with the plates, walls having a tapered cross section, the ends of the walls being angular to conform to the slant of and engage with the walls of the tray, and the coating being thicker at one edge of the plates than at the other edge to provide the tapering sides of the walls, said coating being adapted to be deformed by the freezing of the cubes in the tray so as to prevent sticking of the cubes in the grid and tray, and the semi-flexible plates in the walls enabling manually expelling the ice cubes from between the walls of the grid after removal of the grid from the tray without undue and injurious flexing and deformation of the walls.

3. In a removable grid for a refrigerator tray, a plurality of crossing walls, each of said walls comprising a body of flexible, compressible material having an inverted triangular cross section and provided interiorly with a vertically and longitudinally extending flexible metal plate, said walls defining ice-cube compartments having slanting walls producing tapered ice-cubes, said slanting walls operating to hold the ice-cubes in said grid and tray when the tray is inverted to remove the grid and ice-cubes therefrom and facilitating ejection of individual ice-cubes from the removed grid by manipulating said walls.
